(57) **CLAIM**

The ornamental design for a self-contained inflatable bag sleeping pad, as shown and described.

DESCRIPTION

FIG. 1 is a perspective view of a self-contained inflatable bag sleeping pad showing my new design;

FIG. 2 is a front side view thereof;

FIG. 3 is a rear side view thereof;

FIG. 4 is a right side view thereof;

FIG. 5 is a left side view thereof;

FIG. 6 is a bottom plan view thereof; and,

FIG. 7 is a top plan view thereof.

The broken lines shown in the drawings are included for the purpose of illustrating unclaimed portions of the self-contained inflatable bag sleeping pad and form no part of the claimed design.
